US00D991620S

(12) **United States Design Patent** (10) **Patent No.:** **US D991,620 S**
(45) **Date of Patent:** **** Jul. 4, 2023**

(54) **SAFE BOX**

(71) Applicant: **Jink Solutions Pty. Ltd.**, Ashgrove (AU)

(72) Inventor: **John Paul Wanis**, Ashgrove (AU)

(73) Assignee: **Jink Solutions Pty. Ltd.**, Qld (AU)

(**) Term: **15 Years**

(21) Appl. No.: **29/796,524**

(22) Filed: **Jun. 24, 2021**

(51) **LOC (14) Cl.** **99-00**

(52) **U.S. Cl.** ..... **USPC D99/28**

CLAIM

The ornamental design for a safe box, as shown and described.

DESCRIPTION

The patent or application file contains at least one drawing executed in color. Copies of this patent or patent application publication with color drawing(s) will be provided by the Office upon request and payment of the necessary fee.

FIG. 1 is a perspective view of a safe box, showing my new design;

FIG. 2 is a front elevational view thereof;

FIG. 3 is a rear elevational view thereof;

FIG. 4 is a left side elevational view thereof;

FIG. 5 is a right side elevational view thereof; and,

FIG. 6 is a top plan view thereof.

All surfaces not shown form no part of the claimed design.

**1 Claim, 6 Drawing Sheets
(6 of 6 Drawing Sheet(s) Filed in Color)**
